UNITED STATES PATENT OFFICE.

FRANCIS D. BOYLE, OF TOLEDO, OHIO.

PAD FOR UPHOLSTERED FURNITURE.

No. 813,616.

Specification of Letters Patent.

Patented Feb. 27, 1906

Application filed January 23, 1905. Serial No. 242,342.

To all whom it may concern:

Be it known that I, FRANCIS D. BOYLE, a citizen of the United States, residing at Toledo, in the county of Lucas and State of Ohio, have invented certain new and useful Improvements in Pads for Upholstered Furniture; and I do declare the following to be a full, clear, and exact description of the invention, such as will enable others skilled in the art to which it appertains to make and use the same.

My invention is an improved pad for upholstered furniture, couches, sofas, and the like, of the style known as "roll edge" or "imperial roll edge" now in vogue; and it consists in a pad-cover having its central pad, roll-edge pads, and border-pieces secured together and to the lining or under cover, so that the pad is completely finished before it is secured on the article of furniture which it is designed to cover, as hereinafter described and claimed.

In the accompanying drawings, Figure 1 is a sectional perspective view of a portion of a couch provided with my improved roll-edge cover-pad. Fig. 2 is a transverse sectional view of the same, showing the manner of stuffing the center pad and the edge rolls in accordance with my invention. Fig. 3 is a partial longitudinal sectional view of the same. Fig. 4 is a detail view of the tray for stuffing the roll-edge pieces.

I will first describe my improved roll-edge cover-pad and my method of making the same.

The lining or under cover 1, which is of canvas, burlap, or other suitable material, is of the length and width required to cover the springs of the couch or other article of furniture and to partly or entirely cover the sides thereof, as may be desired. On the central portion of the lining and at suitable distances from the sides thereof is placed the center piece 2 of the cover or pad, which is of the required length and width and is secured at its edges to the lining by stitching it thereto, as at 3. This stitching may be readily done on a sewing-machine. I also provide roll-edge cover-pieces 4 and welt-pieces 5. Welt-cords 6 of suitable size are secured in the edges of the welt-pieces, which are turned over said cords. The welt-pieces are here shown as stitched directly to the lining or under cover, and the roll-edge cover pieces 4

are shown as stitched at their edges to the 55 welt-pieces. If preferred, the edges of each welt-piece may be secured between the proximate edges of the center piece and one of the roll-edge pieces, and said center piece, welt-pieces, and roll-edge pieces also secured to the 60 lining or under cover by a single line of stitching. I do not, however, limit myself in this particular. At the outerside of each roll-edge piece is secured a similar welt-piece 7, which is likewise filled by a suitable welt-cord 8, and a 65 border-piece 9 has its inner or upper edge also secured to the outer edge of each roll-edge piece. If preferred, the welt-piece 7 may be secured to the roll-edge piece and border-piece, said roll-edge piece, welt-piece, 70 and border-piece also secured to the lining or under cover by a single line of stitching. If the border-pieces are to be ruffled or gathered, the ruffling or gathering must be done prior to sewing them in place at the sides of 75 the pad. The center-piece is also secured to the under cover by a transverse row of stitching, as at 10, to form the division between the head-piece and body portion of the pad.

Having thus secured the pieces of my improved pad together, the center pad formed by the under cover and center piece 2 and the edge rolls formed by the lining or under cover and the roll-edge pieces are stuffed and their ends then secured together by stitching, thus completing the making of the pad or cover before it is placed on the article of furniture for which it is designed.

In accordance with my invention I employ for stuffing the center-pad portion a stuffing-tray *a* of suitable length, comprising a bottom and side flanges, which stuffing-tray after having been filled with the stuffing material is inserted lengthwise between the lining or under cover and the center piece 2 to place 90 the stuffing material between them, and the operator then draws out the tray in such manner as to leave the stuffing material in place between the cover-piece 2 and the lining or under cover 1. A tray *b* of the required 95 shape is also employed for inserting the stuffing material between the lining or under cover and the roll-edge pieces to form the edge-roll pads. In securing my improved pad to an article of furniture it is only necessary after appropriately placing the same thereon to secure the side portions of the 100 lining or under cover and the border-pieces 105

to the sides of the article of furniture and to also secure the ends of the pad to the ends thereof, as will be understood.

Heretofore it has been the practice to first 5 form and secure the center pad on the article of furniture to be covered and afterward separately form and secure the roll-edge pads, and it has been necessary to do all the stitching by hand, and this style of uphol- 10 stering has necessarily required the services of the most skilful upholsterers. My improved pad may be made in accordance with my improved method by comparatively un- skilled persons, and all of the sewing required 15 may be readily done on a sewing-machine, and hence my invention effects a very material economy in the production of upholstered furniture of this class.

From the foregoing description, taken in 20 connection with the accompanying drawings, the construction and operation of the invention will be readily understood without requiring a more extended explanation.

Various changes in the form, proportion, 25 and the minor details of construction may be

resorted to without departing from the principle or sacrificing any of the advantages of this invention.

Having thus fully described my invention, what I claim as new, and desire to secure by 30 Letters Patent, is—

A pad for roll-edge upholstered furniture, comprising a lining or under cover, a center piece, having its edges stitched to said lining or under cover, a welt-piece and a roll-edge 35 piece having their edges stitched together and secured to the under cover by stitching, the stitching which secures said center piece, welt-piece, roll-edge piece and lining together, being independent of and unaffected 40 by the devices employed to secure the pad to the furniture.

In testimony whereof I have hereunto set my hand in presence of two subscribing wit- nesses.

FRANCIS D. BOYLE.
